CLAIM

The ornamental design for a carrying handles with attachment therefor, as shown in the Figures.

DESCRIPTION

FIG. 1 is a top perspective view of a set of carrying handles with attachment therefor showing our new design;

FIG. 2 is a top plan view thereof;

FIG. 3 is a right side elevational view thereof, the undisclosed side being the same; and,

FIG. 4 is a front elevational view thereof, the undisclosed rear being the same.

The broken lines shown in all views are for illustrative purposes only and form no part of the claimed design.

FIG. 1.

FIG. 2.

FIG. 3.

FIG. 4.
